DRAWWORKS

Daniel W. Walters, West Los Angeles, Calif., assignor, by mesne assignments, to The National Superior Company, Toledo, Ohio, a corporation of Delaware

Application September 13, 1933, Serial No. 689,233

12 Claims. (Cl. 255—19)

This invention relates to rotary drawworks, and more particularly to a rotary drawworks as utilized in the rotary process of drilling oil, gas or water wells.

5 An object of this invention is to provide a rotary drawworks applicable for use in a drilling rig as utilized for carrying out the rotary process of drilling wells; the prime mover for which drilling rig is a uni-directional means such, for example, as a gas engine or an internal combustion engine which may be of the Diesel type.

Another object of this invention is to provide a rotary drawworks in which there is provided a new and novel type of drive to a member mounted on 15 the drumshaft of the drawworks, which member can be engaged to drive either the hoisting drum or the rotary machine or both.

Another object of this invention is to provide a rotary drawworks which is particularly applicable for use in connection with an internal combustion engine drive, which drawworks includes a shaft driven from the internal combustion engine in a single direction, a drawworks or hoisting drum, and a rotary machine drive means 25 and a transmission connecting means between the driven shaft and the drawworks drumshaft providing for the driving of the drawworks drumshaft or a rotary drive sprocket in either direction as desired from the uni-directional internal combustion engine.

Another object of this invention is to provide a self-contained drawworks unit which can be readily transported in the field.

Another object of this invention is to provide a drawworks in which forward and reverse transmission means are provided in order to adapt the drawworks to an engine drive of the non-reversing type.

Other objects and advantages of this invention 40 it is believed will be apparent from the following detailed description of a preferred embodiment thereof as illustrated in the accompanying drawings.

In the drawings:

45 Figure 1 is a diagrammatic plan view of a rotary well drilling rig in which there is adapted a rotary drawworks and drive means embodying my invention.

Figure 2 is a side elevation of the drilling rig.

50 Figure 3 is a front elevation partly in vertical section of the rotary drawworks embodying my invention.

Figure 4 is a rear elevation partly in vertical section of the rotary drawworks embodying my 55 invention.

Figure 5 is a side elevation of the rotary drawworks.

Figure 6 is a fragmental plan view partly in section illustrating the assembly of the clutch operating foot levers.

Figure 7 is a rear elevation partly in vertical mid-section of the modified form of the drawworks embodying my invention.

In the preferred embodiment of my invention as illustrated in the accompanying drawings there 10 is illustrated a uni-directional prime mover or internal combustion engine A, a drawworks B, driven from the prime mover A by a multiple belt transmission C. A rotary machine D is driven from the drawworks B by means of a chain transmission E. A chain transmission F is likewise provided for driving other auxiliary units employed in the rotary process of drilling the well such, for example, as for driving the bailing drum G or a slush or mud circulating pump H (illustrated in dotted lines).

The drawworks B is preferably of the following construction and includes a drum shaft 1, a line shaft 2, and a jack or countershaft 3, all of which are supported in bearings 4 in a frame 5. The frame 5 is formed of two end sections mounted on beams 6 and cross sills 7. The end sections are tied together by means of cross tie rods 8 fitting within pipe spacers 9 to maintain the end frames in alignment.

The jack shaft 3 is driven from the uni-directional prime mover A, the drive being to a pulley 10 which is secured to one end of the jack shaft 3 and is driven by the multiple belt type of transmission as indicated at C. Rotatably mounted upon the jack shaft 3 is a drive sleeve 11 supported by bearings 12. Mounted on the sleeve 11 is a forward friction clutch mechanism 13 and a reverse clutch mechanism 14.

The friction clutch 13 may be of any suitable or desirable form and as herein illustrated consists of a housing 15 secured to the sleeve 11, and a spider 16 keyed to the shaft 3. The spider 16 has internally expanding clutch shoes 17 which are operable by means of a shifting collar 18 to frictionally connect the shaft 3 with the sleeve 11 for a direct drive. The drive clutch collar 18 is actuated by means of a suitable shifter 19 which is under the operator's control through a connecting rod 20, rock shaft 21, and actuating lever 22.

The reverse clutch mechanism 14 is preferably of the following construction and includes a spider 23 journaled on the shaft 3 and having radially disposed pinions 24 meshing with a bevel 55

gear 25 and a similar bevel gear 26 keyed to the shaft 3.

The bevel gear 25 is secured to the sleeve 11. The outer periphery of the spider 23 is formed to define a brake rim surface 27 around which is fitted a brake band 28. The brake band 28 is anchored to the cross beam 29 as indicated at 30. The live end of the brake band 28 is operably connected to the rock shaft 21 so as to obtain a coordinated control for the direct clutch 13 and the reverse clutch 14 through the single operating lever 22. The operating range of the lever 22 is such as to include a forward position when the clutch 13 is engaged and the band 28 is released and a reverse position when the clutch 13 is released and the reverse band 28 is engaged to hold the spider 23 stationary.

With the spider 23 held stationary, the drive sleeve 11 is driven in a direction opposite to the shaft 3 through the bevel gear 26, stationary pinion 24 and bevel gear 25 mounted on the sleeve 11. The operating lever 22 has a notch segment 31 which cooperates with a spring member 32 to retain the lever 22 and its associated mechanism in the forward, reverse and neutral positions as desired.

Means are provided for driving the line shaft 2 from the jack shaft 3, which means are herein illustrated as including a pair of sprockets 33 and 34 which are journaled on the sleeve 11. Splined on the sleeve 11 between the sprockets 33 and 34 is a double faced clutch collar 35 which is adapted to be selectively shifted into driving engagement with the clutch faces 36 or 37 of the sprockets 33 and 34 respectively by means of a clutch shifter 38. The clutch shifter 38 is pivotally supported by a bracket 39 from the frame 5 and is connected by means of a rod 40 with an operating lever 41 which is journaled upon the rock shaft 21. A latch bar 42 is connected with the lever 41 and is provided with three notches 43 to insure retaining the clutch 35 in one of its two operating positions or in its neutral position. Mounted on the end of the jack shaft 3 is a sprocket 44 which is provided to drive auxiliary units of the drilling rig such, for example, as the bailing drum G or the slush pump H. If desired a clutch may be interposed between the sprocket 44 and the shaft 3 to releasably connect the sprocket 44 with the shaft as desired.

The line shaft 2 is provided with sprockets 45 and 46 which are keyed or otherwise secured to the line shaft 2 and are driven by means of suitable transmission chains 47 and 48 from the sprockets 33 and 34 of the jack shaft. In the construction as thus provided it is possible to drive the line shaft 2 with two speeds forward or two speeds in reverse by means of the non-reversible prime mover A. Furthermore, it is to be observed that the drive to the drum G or pump H is unaffected by the direction of drive of the line shaft 2.

Mounted upon the ends of the line shaft 2 are catheads 49 for use in operating pipe tongs and lifting equipment around the derrick in a manner well known to those skilled in the art. Means are provided for driving the drum shaft 1 from the line shaft 2 which means preferably include sprockets 50 and 51 over which chains 52 and 53 are trained and which chains are trained over sprockets 54 and 55 journaled upon the drum shaft 1. Secured to the drum shaft 1 is a drum 56 which may be of any suitable or desirable construction well known to those skilled in the art. The sprockets 54 and 55 are provided with

clutches 57 and 58 for selectively engaging the drives provided from the line shaft 2 to the drum shaft 1. The clutch 57 is termed a one-way clutch and the clutch 58 is a two-way clutch.

In the construction thus provided it will be observed that the drum 56 can be driven at four forward speeds and at two reverse speeds for any given speed of the uni-directional prime mover A. The clutches 57 and 58 are operated by foot levers 59 and 60 through shifters 61 and 62, respectively.

Secured to the end flanges of the drum 56 are brake rims 63. Mounted upon the brake rims 63 are brake bands 64, the live ends of which brake bands are operated by means of a rock shaft 65 connected to a brake lever 66 situated in a plane at right angles to the plane of the brake rims. Means are provided on the drum shaft for driving the rotary machine D through the chain transmission E, which means preferably includes a sprocket 67 which is journaled upon a sleeve 68, which sleeve 68 is in turn journaled on the drum shaft 1. The sprocket 67 is provided with a clutch face 69 and the sprocket 55 is provided with a complementary clutch face 70. When the rotary machine D is inoperative, the drive sprocket 67 is in the position as illustrated in Figure 3. A shifter 71 is provided for shifting the sprocket 67 to the left as viewed in Figure 3 so that the clutch faces 69 and 70 are engaged. The shifter 71 is connected by means of a rod 72 with the foot pedal 13.

As the sprocket 55 is driven at two speeds forward or reverse it is possible to have the same number of speeds and directions of drive for the rotary sprocket 67 and hence for the rotary machine D. When the sprocket 67 is in the inoperative position, the plane of the sprocket teeth thereon is slightly out of alignment with the sprocket on the rotary machine D, but by shifting the sprocket 67 into driving engagement with the sprocket 55, the planes of the sprocket 67 and the sprocket on the rotary machine D come into alignment with the result that there is no misalignment of the transmission chain when driving.

In Figure 7 I have illustrated a modified form of jack shaft drive of the drawworks in which the jack shaft 3a is driven at a forward and reverse direction from the drive sprocket 10a rotatably mounted thereon. The structure illustrated in Figure 7 is similar to that as heretofore described so that similar numerals have been employed with the addition of a suffix "a".

Rotatably mounted on the jack shaft 3a is the drive sprocket 10a which is driven from any suitable form of uni-directional prime mover. The sprocket 10a is positioned between the forward clutch 13a and the reverse clutch 14a.

The clutch 13a consists of a housing 15a connected to the sprocket 10a and a spider 16a having internally expanding clutch shoes 17a which are operable by means of the shifting collar 19a to frictionally connect the drive sprocket 10a with the shaft 3a.

The forward clutch collar 18a is actuated in the same manner as that described for the clutch mechanism 13 as illustrated in Figure 4. The reverse clutch mechanism 14a includes a spider 23a having bevel pinions 24a meshing with a bevel gear 25a non-rotatably mounted with relation to the sprocket 10a and a bevel gear 26a which is keyed to the shaft 3a. The outer periphery of the spider defines a brake rim surface 27a around which is fitted a brake band 28a which

is also anchored and operated in the same manner as described in connection with the reverse clutch in Figure 4.

Journalized on the jack shaft 3a are line shaft 5 drive sprockets 33a and 34a between which is positioned the double faced clutch collar 35a which can be operated to selectively engage either sprocket to drive the line shaft 2 at the desired speed. Sprocket 44a is mounted upon the end 10 of the jack shaft 3a for driving any auxiliary unit of the derrick rig.

Having fully described my invention, it is to be understood that I do not wish to be limited to the details herein set forth, but my invention is of 15 the full scope of the appended claims.

I claim:

1. In a rotary drawworks, the combination of 20 a frame, a line shaft rotatably supported by the frame, a jack shaft rotatably supported by the frame, a drum shaft rotatably supported by the frame, a power take-off drive sprocket rotatably supported on said drum shaft, means to selectively drive the drive sprocket and the drum shaft from the line shaft, a drum supported on said 25 drum shaft and non-rotatably secured relative thereto, means for driving the line shaft from the jack shaft in one direction, means for driving the line shaft from the jack shaft in a reverse direction, said driving means for driving 30 the line shaft in a forward and reverse direction, including a transmission means between said line and jack shafts which is common to the forward and reverse drive means, and means for driving the jack shaft in one direction.

35 2. In a rotary drawworks, the combination of a frame, a drum shaft rotatably supported by the frame, a line shaft rotatably supported by the frame, a jack shaft rotatably supported by the frame, a drum mounted on the drum shaft to be 40 driven therewith, a power take off drive sprocket rotatably supported on the drum shaft, a pair of driven sprockets rotatably mounted on the drum shaft, transmission drive connections between the driven sprockets, line shaft and jack shaft for driving 45 the driven sprockets at a plurality of speeds in one direction, transmission drive connections between one of said driven sprockets, line shaft and jack shaft for driving said driven sprocket in the reverse direction, said 50 transmission drive connections for driving said driven sprocket in a forward and reverse direction including a transmission connection between the line shaft and the jack shaft which is common to the forward and reverse drive connections, clutch means to selectively engage said 55 driven sprockets in driving relation with said drum shaft, means including a clutch connection to connect one of said driven sprockets in driving relation with the power take-off drive sprocket, and a uni-directional prime mover for driving the jack shaft.

3. In a rotary drawworks, the combination of a frame, a drum shaft rotatably supported by the frame, a line shaft rotatably supported by the frame, a jack shaft rotatably supported by the frame, a drum mounted on the drum shaft to be 60 driven therewith, a power take-off sprocket rotatably supported on the drum shaft, transmission drive connections between the drum shaft, line shaft and jack shaft for driving the drum at a plurality of speeds in one direction, transmission drive connections between the drum shaft, line shaft and jack shaft for driving the drum in the reverse direction, transmission drive connections between the power take-off drive 65

sprocket, line shaft and jack shaft for driving the power take-off drive sprocket at a plurality of speeds in one direction, transmission drive connections between the power take-off drive sprocket, line shaft and jack shaft for driving the power take-off drive sprocket in the reverse direction, said transmission drive connections for driving said driven sprocket and drum independently in a forward and a reverse direction, including a transmission connection between the line shaft 10 and the jack shaft which is common to the forward and reverse drive connections, and a uni-directional prime mover for driving the jack shaft.

4. In a drawworks, the combination of spaced bearing supports, a drum shaft and a jack shaft 15 rotatably supported by said bearing supports, a drum mounted on the drum shaft, a sleeve rotatably mounted on said jack shaft, a forward clutch positioned at the end of the sleeve adapted to connect the jack shaft and the sleeve for driving 20 the latter in a forward direction, a reverse clutch positioned at the other end of the sleeve adapted to connect the jack shaft and the sleeve for driving the latter in a reverse direction, coordinated operating means to selectively engage either 25 clutch, a uni-directional drive means on the jack shaft, a plurality of drive means rotatably mounted on the sleeve, transmission connections between said latter drive means and the drum shaft for driving said drum, and clutch means on 30 said sleeve to selectively engage any of the drive means thereon to drive the drum at a plurality of forward or reverse speeds.

5. In a drawworks, the combination of a frame, a drive shaft rotatably supported on the frame, 35 means to drive the drive shaft, a drum shaft carrying a spooling drum being rotatably supported on said frame, a clutch faced sprocket having a sleeve extension rotatably mounted on the drum shaft, a sprocket mounted on the drive 40 shaft for driving the sprocket on the drum shaft, a clutch slidably mounted on the drum shaft to engage one of the clutch faces on the sprocket to drive the drum shaft as desired, a clutch faced sprocket rotatably and slidably mounted on the 45 sleeve extension of the first named clutch faced sprocket, means to shift one of the clutch faced sprockets axially to engage the complementary clutch faces to effect a driving connection, and a transmission connection from the second named 50 clutch faced sprocket to an auxiliary driven member.

6. In a device of the class described, the combination of a drum shaft, a drum mounted on the drum shaft, a frame including spaced members 55 for rotatably supporting the drum shaft, the drum having an outwardly extending brake rim at one end, a sprocket and clutch drive means mounted on the drum shaft partially within the space defined by said outwardly extending brake rim for 60 driving the drum, a power take-off sprocket mounted on the drum shaft between the first said sprocket and the supporting member, and clutch means for clutching the latter said sprocket to the first said sprocket.

65 7. In a device of the class described, the combination of a drum shaft, a drum mounted on the drum shaft, a frame including spaced members for rotatably supporting the drum shaft, the drum having an outwardly extending brake rim at one 70 end, a clutch faced driven sprocket having a sleeve extension rotatably mounted on the drum shaft, a clutch slidably and non-rotatably mounted on the drum shaft partially within the space defined by said outwardly extending brake 75

- rim, means to shift said clutch into driving engagement with said clutch faced driven sprocket, a clutch faced power take-off sprocket rotatably and slidably mounted on said sleeve extension between said driven sprocket and the adjacent shaft supporting member, and means to shift said power take-off sprocket axially into driving engagement with said clutch faced driven sprocket.
8. In a drawworks, the combination of spaced bearing supports, a drum shaft carrying a spooling drum being rotatably supported on said supports, a drive shaft rotatably supported on said supports, means to drive said drive shaft, a transmission member on the drive shaft, a transmission member on the drum shaft operatively connected with the drive shaft transmission member, clutch means to engage with the transmission member on the drum shaft to drive the drum, a rotary machine drive member rotatably supported in co-axial relation to the drum shaft transmission member, and means to shift the rotary machine drive member axially into driving engagement with the transmission member on said drum shaft.
9. In a drawworks, the combination of a frame, a drive shaft rotatably supported on the frame, a drum shaft assembly including a shaft, a spooling drum mounted thereon, a drive sprocket rotatably supported on the drum shaft, clutch means to selectively engage said drive sprocket to drive the spooling drum, a rotary machine drive sprocket, said drive sprocket and rotary machine drive sprocket being provided with complementary clutch means to form a driving connection, means to shift said rotary machine drive sprocket axially out of driving engagement with the drive sprocket, means to drive said drive shaft, and a sprocket on said drive shaft for driving the first named drive sprocket on the drum shaft.
10. In a drawworks, the combination of a drum shaft, a jack shaft, means to support said shafts, a drum mounted on the drum shaft, a sleeve rotatably mounted on the jack shaft, a releasable forward clutch positioned at one end of the sleeve adapted to connect the jack shaft and the sleeve for driving the latter in a forward direction, a releasable reverse clutch positioned at the other end of the sleeve adapted to connect the jack
- shaft and the sleeve for driving the latter in a reverse direction, coordinated operating means to selectively engage either clutch, a pair of drive means rotatably mounted on the sleeve, transmission connections between said latter drive means and the drum shaft for driving said drum, a clutch positioned on said sleeve between said drive means, and means to shift said clutch to engage either of said drive means to provide a drive connection between said sleeve and either of said drive means for driving the drum in either a forward or reverse direction.
11. In a drawworks, the combination of a drum shaft, a jack shaft, means to support said shafts, a drum mounted on the drum shaft, a sleeve rotatably mounted on the jack shaft, means to drive said sleeve from a uni-directional source of power, a releasable forward clutch means interposed between one end of said sleeve and said jack shaft for driving said shaft in a forward direction, a releasable reverse clutch means interposed between the other end of said sleeve and said jack shaft for driving said shaft in a reverse direction, operating means to selectively engage either of said clutch means for driving the jack shaft in either direction, and transmission connections between the jack shaft and the drum shaft for driving said drum.
12. In a drawworks, the combination of a drum shaft, a jack shaft, a line shaft, means to support said shafts, a drum mounted on the drum shaft, a sleeve rotatably mounted on the jack shaft, means to drive said sleeve from a uni-directional source of power, a releasable forward clutch means interposed between one end of the sleeve and said jack shaft for driving said shaft in a forward direction, a releasable reverse clutch means interposed between the other end of said sleeve and said jack shaft for driving said shaft in a reverse direction, transmission connections between the jack shaft and the line shaft and between the line shaft and the drum shaft for driving the latter shaft at a plurality of speeds, a member on said sleeve driven from a uni-directional source of power, and operating means to selectively engage either of said clutch means for driving the jack shaft in either direction.

DANIEL W. WALTERS.
